MULTI-WAY TUMBLER SWITCH

Henry William Trevaskis, Solihull, England, assignor to Dunlop Rubber Company Limited, London County, England, a British company

Application November 9, 1954, Serial No. 467,840

1 Claim. (Cl. 200—6)

This invention relates to tumbler switches for the control of electrical apparatus and circuits, and more particularly to multi-way tumbler switches for the selective control of electrical apparatus for actuating aircraft aileron and elevator trimming tabs.

Four-way tumbler switches for the control of aircraft trimming tabs are known, and are usually mounted on the aircraft control stick and are selectively operated by the pilot to energize one of four electrical circuits which control the electric motors and screwjacks of an elevator or aileron trimming tab, whereby the trim of the aircraft may be readily adjusted.

The object of the present invention is to provide a novel type of multi-way tumbler switch.

According to the invention a multi-way electric tumbler switch comprises a housing, a plurality of pairs of electrical contacts within said housing, said contacts being arranged on a common pitch circle and each pair of contacts being adapted to be connected across a source of potential, a tumbler pivotable to bridge any one of said pairs of contacts and resilient means selectively operable to pivot said tumbler.

Preferably the tumbler comprises a rectangular block of non-conductive material of square cross section, one end of which abuts the base of the housing. A bearing member having a conical recess in the centre thereof extends axially from the other end whereby side thrust on said recess causes the block to move angularly about one of the edges of that end which abuts the base of the housing.

At the end adjacent the bearing member, metal facings are secured to each of the faces of the tumbler which lie adjacent each pair of contacts, whereby angular movement of the tumbler will cause one of the facings to engage with one pair of contacts to complete an electrical circuit.

Preferably also the means for moving the tumbler comprise an operating member having a conical projection extending axially from one end thereof to engage the conical recess of the bearing member of the tumbler. A spring guide extends axially from the base of the conical projection, and the member is held in position by means of a helical spring surrounding said spring guide, said spring being compressed between the closed end of an operating thimble and a flange extending outwardly from said spring guide. Movement of the operating thimble in one direction will therefore cause the tumbler to move in the opposite direction.

Alternatively the operating thimble may be of square cross-section and associated with recesses in the housing to guide the movement of said thimble.

The invention will now be described with reference to the accompanying drawings of which,

Figure 1 is a sectional view of a multiway tumbler switch constructed according to the invention.

Figure 2 is a view of the tumbler switch illustrated in Figure 1 taken on the line A—A, looking in the direction of the arrows.

2

According to one embodiment of the invention (Figures 1 and 2), a housing 1 to be connected to an aircraft control stick is stepped intermediate its ends, and a plug of insulating material 2 seals the end of the larger diameter portion of the housing 1 remote from the step 3. Four pairs of electrical contacts 4, 4 extend axially from the insulated plug 2 into the housing, being substantially equidistantly spaced on a common pitch circle.

The plug of insulating material 2 is formed in the centre thereof with a square recess 5 having outwardly tapering sides, each side being parallel to one pair of contacts. A further recess 6 of smaller area, is formed symmetrical with and in the base of the recess 5 whereby a step 7 is formed, the smaller recess 6 having sides which extend substantially parallel with the axis of the housing. A rectangular tumbler 8 of non-conductive material and square cross-section is located on the step 7, said tumbler 8 being provided with a projecting portion 9 of frusto-conical form the smaller diameter of which is remote from the rectangular portion, said frusto-conical portion 9 fitting into the smaller recess 6.

A bearing member 10 extends axially from the other end of the tumbler 8 having a conical recess 11 in the centre thereof, and metal facings 12 are secured to each of those faces of the tumbler which are adjacent a pair of contacts. The facings 12 extend only part way along the axial length of each face of the tumbler from the end adjacent the bearing member.

A collar 13 having an outwardly extending flange 14 at one end is located within the smaller diameter portion of the housing, being secured therein by means of the flange 14 which abuts the step 3 of the housing, and which is held against the said step 3 by means of an insulating washer 15 which abuts the adjacent end of the pairs of contacts 4, 4 on the side thereof remote from the said flange 14. The other end of the collar 13 is inwardly turned to form an annular recess 16 between the inner periphery of the collar and the inwardly turned portion.

An operating thimble 17 is formed of hollow frusto-conical cross section being closed at the smaller diameter end, and having an outwardly-turned portion formed at the larger diameter end thereby forming an annular recess 18 between the outer periphery of the thimble and the outwardly-turned portion.

The inwardly turned portion of the collar and the outwardly turned portion of the thimble are associated mutually to limit the axial movement of the thimble 17 in one direction, and also to provide a fulcrum about which said thimble may pivot.

An operating member 19 comprising a spring guide 20, an outwardly extending flange 21 and a conical projection 22 is located interior of said operating thimble, the conical projection 22 engaging in the conical recess 11 of the bearing member 10. A helical spring 23 is compressed between the closed end of the operating thimble and the outwardly extending flange 21 and a cover 24 of resilient material secured to the operating thimble encloses the open end of the housing to prevent the ingress of moisture, dirt and the like.

Each pair of contacts are connected to positive and negative sources of potential in a known manner, the positive contacts of each diametrically opposed pair being connected together.

The switch is operated by pivoting the operating thimble 17 in any one of four directions. This movement, acting through the helical spring 23, moves the conical projection 22 in the direction opposite to that of the operating thimble 17. The conical projection thus moves the bearing member 10 causing the tumbler 8 to rock about one edge of its base located in the recess 3 formed

in the base of the housing. Thus pivotal movement of the thimble in one direction will pivot the tumbler in a diametrically opposite direction.

This movement forces one of the facings 12 of the tumbler to bridge the associated pair of contacts and complete the circuit to the desired aileron or elevator trimming tab control mechanism.

Having now described my invention what I claim is:

A snap-action, multi-way electric switch comprising a housing having a rectangular recess in the base thereof, and an inwardly-turned annular lip at the other end, a plurality of pairs of electrical contacts within said housing, said contacts being disposed on a common pitch circle, and each pair of contacts being adapted to be connected across a source of potential, a tumbler having a rectangular base pivotable on any one of the edges of said rectangular recess to bridge any one of said pairs of contacts, an operating rod in pivotable engagement with

5 said tumbler, a frusto-conical member outwardly lipped to engage behind the inwardly-turned lip on the housing, and a spring fitted in compression between said operating rod and said frusto-conical member, whereby angular movement of the frusto-conical member in any of four directions pivots the tumbler in the opposite direction to bridge a pair of contacts.
